BALL COCK VALVE

Herbert D. Clemons, Cheshire, Conn., assignor
to Scovill Manufacturing Company, Waterbury,
Conn., a corporation of Connecticut

Application February 23, 1950, Serial No. 145,842

2 Claims. (Cl. 137—104)

1

This invention relates to ball cock control valves for flush tanks and particularly to a valve silencing means.

One object of this invention is to provide an improved valve silencing means that is adjustable to effect a silencing operation of the valve over a wide range of fluid pressure systems in which the valve may be used.

A further object is to provide an improved control valve of the above character in which the fluid flow is distributed thinly through a long progressively increasing conical passageway to effect the silencing operation.

A still further object is to render the valve self-cleaning in case any sediment is collected in the base of the valve housing, and also to provide means to catch any large particles of dirt or foreign matter and prevent them from jamming or otherwise obstructing the thin conical fluid passageway.

A structure which is a preferred embodiment of my invention is illustrated in the accompanying drawing, in which:

Fig. 1 is a fragmentary view in side elevation of a ball cock valve embodying features of my invention, parts being broken away and shown in vertical section with the valve in closed position.

Fig. 2 is a right end view of the same.

Fig. 3 is a sectional view similar to the upper part of Fig. 1 but showing the valve in open position, and

Fig. 4 is a perspective view of the silencing control sleeve.

Referring now to the drawing in which like reference numerals indicate like parts in the several views, the numeral 10 indicates a supply pipe or riser which is mounted within a tank 11 in the conventional manner. Threadedly attached to the upper end of the riser is a nozzle member 12 having an enlarged hollow interior 13 that converges into a discharge opening 14 at the upper end of said nozzle. The nozzle 12 terminates at its upper end in a valve seat 16 and the exterior surface of the nozzle is in the form of a relatively long conical face 17 that extends uninterruptedly up to the valve seat 16. The nozzle member 12 is provided with an enlarged shouldered portion 18 below the conical face 17 which portion 18 is threaded into a valve casing 20.

The valve casing 20 has a discharge chamber 21, an outlet 22 and a threaded bore 23 in axial alignment with the riser 10. A hush tube 24 is connected to the outlet 22 and extends downwardly to a point adjacent the bottom of the tank 11.

2

The adjustable silencing member is provided in the form of a tubular sleeve 25 having a threaded section 26 for adjustable engagement with the threaded bore 23 of the casing 20. The sleeve 25 extends down into the discharge chamber 21 and is formed at its lower end with an inset portion 27 from which depends an outwardly flaring conical skirt 28 conforming to the angle of the nozzle conical face 17. The upper end of the sleeve 25 is integrally formed with an annulus 29 that extends outwardly from the sleeve 25 and is adapted to overlie the upper surface of the valve casing 20.

The relative position of the conical skirt 27 to the conical face 17 of the nozzle 12 determines the silencing effect of the valve mechanism, and when the valve is installed in a fluid supply line of a high pressure flow system the skirt 28 should be adjusted so that there is only a relatively narrow space 30 provided between the complementary conical surfaces. If the valve is to be installed into a low pressure fluid system then the sleeve 25 is threaded upwardly in the casing 20 to provide a relatively wider conical space 30 between said complementary conical surfaces. The sleeve 25 may be held in adjusted position by a screw 31 threaded into a lug 32 at the upper end of casing 20 and which screw 31 coacts with the annulus 29 of the adjustable sleeve 25 as shown in Fig. 1.

In order to control the flow of water through the valve, a plunger valve 33 is arranged within the sleeve 25 and is provided on its lower end with a sealing disc 34 of flexible or resilient material and held in place by a flanged collar 35 threaded to the plunger valve 33. The disc 34 is compressed against the nozzle valve seat 16 to close the valve and removed therefrom for opening the valve by a conventional form of mechanism as now explained.

The valve casing 20 is provided with an outwardly extending bracket 36 disposed opposite the locking screw 31 and provided with upper and lower pivot eyes 37 and 38. A valve lever 39 is pivoted to the upper bracket eye 37 as by a thumb screw 40 and has one end engaged in a slot 41 in a post 42 extending upwardly from the plunger valve 33. The opposite end of the valve lever 39 is connected to a float arm 43 by a hinging cross link 44, the float arm in turn being pivotally connected to the bracket lower eye 38 as by screw 45. (See Fig. 1.)

When the plunger valve 33 is opened by the lowering of the float arm 43, the water first fills the valve chamber 46 in sleeve 25 and is then directed downwardly through the conical annulus

30 thus breaking down and spreading out the water stream incident to its discharge into the discharge chamber 21, thus producing a substantially noiseless discharge. In view of the fact that the silencing sleeve 25 is threaded into the casing 20 it may be readily adjusted for maximum operating silence of the valve under a wide range of pressure conditions. Furthermore, the silencing sleeve in being removable from the casing 25 may be renewed or cleaned as desired.

It is to be noted that the inset portion 27 of the silencing sleeve 25 is located some distance below the valve seat 16 and this provides a free space within the valve chamber 46 within which any large pieces of dirt or foreign matter may be collected rather than to be forced down into the conical annulus 30. Also the fact that the lower end of the conical skirt 28 is positioned above the base of the discharge chamber 21 precludes the possibility of sediment accumulating and building up at that part of the chamber to the detriment of the valve efficiency.

By making the valve seat 16 high in the chamber 21, I am able cheaply to provide an unusually long conical surface on the outside of the nozzle 12. A long interior conical surface on the sleeve 25 can easily be provided to complete the long conical annulus passageway 30 through which the water flows downwardly. The water in reversing itself washes over the valve seat 16 keeping it clean and the long downward conical passageway 30 provides the optimum silencing effect.

One form of the invention is presented herein for the purpose of exemplification. It will, however, be appreciated that the invention is susceptible of embodiment in other structurally modified forms coming equally within the scope of the appended claims.

What I claim is:

1. A ball cock comprising in combination a valve casing having a chamber and an interiorly threaded portion at its upper end, a nozzle having

means for connection to the usual riser supply pipe and projecting upwardly into said chamber and terminating in a valve seat a substantial distance above the bottom of said chamber, said nozzle member having an exterior conical surface extending uninterruptedly from said valve seat to the bottom of the chamber, a regulating sleeve threaded into the upper part of said chamber and having at its lower end a skirt with an interior conical surface surrounding and complementary to the conical surface of said nozzle and being spaced therefrom depending upon the longitudinal adjustment of said regulator for varying the rate of flow through the conical annulus between said conical surfaces, which annulus gradually increases in size from closely adjacent said valve seat to a point closely adjacent the bottom of said chamber, the length of said conical annulus being substantially greater than its diameter at the entrance end adjacent the valve seat to quiet the flow of water over and away from said valve seat, and a plunger valve within said regulator sleeve for coaction with said valve seat.

2. A ball cock according to the preceding claim wherein there is provided between the regulator sleeve and the nozzle end a small chamber communicating with the entrance to the conical annulus.

HERBERT D. CLEMONS.
